UNITED STATES PATENT OFFICE.

DAVID SCHULER, OF KERRTOWN, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,074,214.

Specification of Letters Patent. Patented Sept. 30, 1913.

Application filed September 9, 1910. Serial No. 581,156.

To all whom it may concern:

Be it known that I, DAVID SCHULER, a resident of Kerrtown, in the county of Crawford and State of Pennsylvania, have invented a new and useful Improvement in Garment-Stays, of which the following is a specification.

This invention relates to stays for garments and the like, and more particularly to wire stays for corsets.

The object of the invention is to provide a stay for this purpose which will readily yield edgewise as well as sidewise, which is perfectly elastic, and in which the bending can not be concentrated at any point or points, thereby avoiding short bends, with the consequent crystallization and breakage.

The invention comprises a stay constructed as hereinafter described and claimed.

In the accompanying drawing Figure 1 is an enlarged face view of one form of stay embodying the invention; and Fig. 2 is a cross section on the line 2—2, Fig. 1.

The wire is bent alternately back and forth to form the oppositely disposed loops 2, arranged alternately progressively along the stay and extending laterally across the width thereof and preferably having rounded outer or closed ends forming the edges 30 of the stay. All of the loops lie in the same plane. The crossings 4, instead of extending straight across from edge to edge are deflected out of the straight line in the plane of the stay, giving the stay crossings as a whole a general angular appearance in plan view, with a bend 5 substantially at the median longitudinal line of the stay, the portions of the crossings on opposite sides of said median line being inclined in opposite directions. These crossings may furthermore be more or less wavy or sinuous, as indicated at 6. This produces a row of wave-like portions all curved in one direction along the center or median line of the

45 stay and two rows of other wave-like portions, all curved in the opposite direction along the side edges of the stay. This sinuous or wavy form disposes of a greater

length of wire in a given length of stay, and therefore makes the stay more flexible 50 and less liable to breakage or permanent distortion or set than if the crossings were straight.

By having the crossings deflected in the plane of the stay as described, the wire is so 55 disposed that in the flatwise bending these crossings take care of the bending stresses by a torsion or twisting and also by transverse bending. As a consequence, the stay is stiffer against stresses tending to bend the 60 same flatwise than it would be if the crossings extended straight across from side to side, in which latter event such crossings would act purely by torsional twist when the stay is bent flatwise. At the same time the long 65 length of wire in a given length of stay makes it very flexible against edgewise bending and prevents it from buckling or twisting when bent edgewise.

To further stiffen the stay, and also to 70 render the same stiffer when bent in one flatwise direction than when bent in the other, the crossings 4 are also deflected out of the plane of the stay, so as to give to the stay as a whole a concavo-convex form in 75 cross section and a general grooved or corrugated appearance longitudinally, as shown in Fig. 2. This not only protects the stay as a whole against flatwise bending stresses, but makes it stiffer against stresses tending 80 to bend it toward the convex side than against stresses tending to bend it in the opposite direction, and particularly adapts the structure as a garment stay where the stresses are almost exclusively in one direction. 85

The stay is practically flat and of comparatively light weight. It contains such a long length of wire that short bending, or concentration of bending stresses at any 90 point is practically avoided, and as a consequence it is practically unbreakable.

What I claim is:

A garment stay formed of wire bent back and forth across the entire width of the stay 95 in alternately progressive loops, the connect-

ing crossings being bent in the plane of the stay into wavy or undulating form to produce a row of wave like portions all curved in one direction along the center line of the stay and rows of other wave like portions curved in the opposite direction along each side edge of the stay.

In testimony whereof, I have hereunto set my hand.

DAVID SCHULER.
